[57] CLAIM

The ornamental design for a rack for supporting a plurality of horizontally oriented rings, as shown and described.

DESCRIPTION

FIG. 1 is a perspective view of the rack for supporting a plurality of horizontally oriented rings showing our new design.

FIG. 2 is a front elevational view, the rear view being identical thereto;

FIG. 3 is a side elevational view, the opposite side being identical thereto;

FIG. 4 is a bottom plan view thereof; and

FIG. 5 is a top plan view thereof.
